MATERIAL HANDLING APPARATUS

Andrew Neuhart, West View, Pa., assignor to
Miller Printing Machinery Co., Pittsburgh, Pa.,
a corporation of Pennsylvania

Application May 31, 1950, Serial No. 165,146

15 Claims. (Cl. 271—62)

1 This invention relates to material handling apparatus. It has to do with certain structural features of material handling apparatus having advantages in utility, economy and simplicity of operation.

In its broader aspects my invention is applicable to material handling apparatus generally. I have utilized the invention in the feeding of sheets to presses and in certain of its narrower aspects the invention has especial utility in presses and feeders therefor.

For purposes of explanation and illustration I shall describe the invention in relation to its embodiment in a feeder for presses.

The particular feeder in which the invention is disclosed as being embodied is a sheet feeder for delivering sheets sequentially to a cylinder, as to the impression cylinder of a flat bed and cylinder type printing or cutting and creasing press. In such a press sheets are delivered along a feed board to the cylinder where they are taken by grippers on the cylinder, each sheet in turn being carried by the cylinder through one revolution thereof during which it is pressed against the form on the bed. The sheet is then removed from the cylinder and delivered to a pile.

The sheets being fed are supplied in a pile in the feeder. Sheets are taken one by one from the top of the pile and delivered along the feed board to the cylinder as above described. The feeder herein disclosed is of the type in which the sheets are taken one by one from the top of the pile by suction fingers. Those suction fingers deliver each sheet to a second set of suction fingers which moves the sheet forward along the feed board to a position intermediate the ends of the feed board. When the sheet reaches the intermediate position it is released by the second set of suction fingers and held temporarily on the feed board by suction. The second set of suction fingers is then retracted to pick up the succeeding sheet and a third set of suction fingers takes the sheet from its intermediate position on the feed board and delivers it into registry with the cylinder whence it is taken by the cylinder grippers. The two sets of suction fingers operating on the feed board (i. e., the second and third sets above referred to) may be mounted on a common carriage oscillatable along the feed board so that they automatically operate in synchronism; when one of those sets of suction fingers is feeding a sheet from the suction fingers which remove it from the top of the pile to the intermediate position on the feed board the other thereof is feeding the preceding sheet along the feed board from the intermediate position to the position of registry with the cylinder. Side registering means are provided for insuring proper side registry of the sheets.

As sheets are taken from the top of the pile in

2 the feeder that pile becomes shorter and to compensate for the gradual reduction in the height of the pile the pile is moved upwardly step by step. The upward movement of the pile must be properly regulated to insure that the top of the pile is always at the proper height. This is done by what is known in the art as a "pile governor."

It is difficult or impossible to work on the form or the cylinder or, indeed, any of the mechanism located generally beneath the feed board when the latter is in operative position. Hence it is known in the art to move the feed board to inoperative or relatively out of the way position when such work is to be done. Feed board used in feeders of the type above referred to have generally been pivoted at the end thereof remote from the cylinder. Because feed boards have been so pivoted it has generally been necessary, due to the mass of the feed board and the mechanism carried thereby and the power required to move the feed board between operative and inoperative positions, to employ mechanism providing great mechanical advantage for effecting the movement. The mechanism heretofore generally employed has included a manually operable crank turning a worm meshing with a worm wheel connected with the feed board so that when the crank is turned the feed board is swung up or down very slowly. Valuable time is wasted and unnecessary energy is expended. It may be necessary to move the feed board between operative and inoperative positions a considerable number of times in making ready a form for printing or cutt'ng and creasing and if the feed board has to be laboriously cranked back and forth each time the working efficiency of the apparatus is greatly reduced.

Sometimes when particular work is to be done inside the press it is not sufficient to simply move the feed board to inoperative position; it may be desired to move the entire feeder to out of the way position. It has heretofore been customary to connect the feeder to the press frame by a vertical pivot so that the entire feeder can be swung horizontally between operative position in relation to the press and inoperative position when the press and the inside of the feeder are laid wide open for access. Such mounting of the feeder has posed problems in driving the feeder carriage and the pile governor. Driving mechanism has heretofore been employed which either has been subject to disconnection when the feeder is swung out to inoperative position or has been unduly complex and expensive or both. Generally the driving mechanism for the feeder carriage and the pile governor has included separable connections from the press drive which are disconnected each time the feeder is swung out to inoperative position and reconnected each time the feeder is swung back to

operative position with consequent wear on the parts due to friction and impact.

The mechanism heretofore employed for operating the pile governor has been unduly complex and expensive. It has included, in addition to an individual separable driving connection from the press drive, separate means for operating the feeler engaging the top of the pile of sheets in the feeder and for operating the pile elevator with control means interposed between such separate means activating the pile elevator when the feeler descends a predetermined distance. This has entailed duplication of parts. The pile elevator drive has included a ratchet and a pawl cooperating with the ratchet, the pawl being stationary except when it is activated by the feeler. Provision for activating the pawl under such circumstances has necessitated the employment of unduly complicated mechanism including an undue number of parts. Moreover, the feeler operating mechanism has been undesirably complex and has involved the continual oscillation of parts of considerable mass.

I have devised material handling apparatus which may be embodied in a feeder of the general type above referred to but which is largely new in construction and which solves certain of the above mentioned problems. Other of the above mentioned problems have been solved by August A. Saul whose application Serial No. 165,297 was filed May 31, 1950. The Saul application and this application disclose the same feeder because the improvements which I have made and those which Mr. Saul has made mutually cooperate with each other, but my improvements are claimed in this application while those made by Mr. Saul are claimed in his application.

I provide improved, simplified, and relatively rugged and foolproof mechanism for operating the pile governor. My mechanism is of such relative simplicity and effectiveness as compared with pile governor operating mechanism heretofore employed that I can manufacture at greatly reduced cost a feeder including pile governor operating mechanism accomplishing all the functions of prior mechanisms of the type in question and, indeed, accomplishing some of those functions in superior manner.

My pile governor operating mechanism is preferably such that it may remain connected with the press drive at all times, even when the feeder is swung out to inoperative position, eliminating entirely the provision of a separable connection and also obviating wear on the parts of such a connection due to friction and impact upon movement of the feeder into and out of operative position. I preferably mount upon the vertical pivot which pivotally connects the feeder to the press frame an operating device which is adapted to oscillate vertically along that pivot. Oscillation is effected by a crank device operated from the main press drive. There may be employed a sleeve disposed about the vertical pivot, which sleeve may be utilized in driving the feeder carriage as claimed in the Saul application. If such a sleeve is utilized it desirably maintains fixed orientation relatively to the press during swinging of the feeder about the vertical pivot into and out of operative relationship with respect to the press. I preferably mount the device for operating the pile governor upon the above mentioned sleeve or at least provide for guiding it in oscillatory up and down movement with the sleeve along the vertical pivot which connects the feeder to the press. However, the operating device turns

about the pivot with the feeder when the feeder is swung between operative and inoperative positions. Preferably a connecting member such as a rod extends from the operating device to the pile governor, and such connecting member is guided in the feeder frame so that when the feeder is swung about the axis of the vertical pivot the connecting member causes turning of the operating device about the axis of the pivot.

10 I employ but a single connecting member from the operating device to the pile governor, the pile governor mechanism being greatly simplified and at the same time rendered more efficient than prior pile governor mechanisms. The single connecting member oscillates the feeler which engages the top of the pile and also oscillates the pawl for operating the pile elevator. The pawl oscillates continuously during operation of the feeder. It is normally held out of engagement with the ratchet by a detent which in turn is rendered inoperative by means connected with the feeler when the feeler descends to a predetermined level. Such mechanism preferably includes a cam which turns the detent out of the path of a portion of the pawl permitting the pawl to move into engagement with the ratchet to bring about elevation of the pile. When the top of the pile has been elevated to the proper extent the detent again becomes operative for holding the pawl out of engagement with the ratchet and the pawl continues to oscillate in inoperative position until the feeler again causes the cam to move the detent out of the position in which it maintains the pawl inoperative.

15 20 25 30 35 40 45 50

35 The feeler is preferably spring operated in both directions. Desirably it is carried by a bell crank lever to which a tension coil spring is connected tending always to raise the feeler upwardly out of contact with the top of the pile. A compression coil spring tends to move the feeler downwardly into engagement with the top of the pile. The operating mechanism includes means pressing against the compression coil spring until the tension coil spring is overcome whereupon the feeler moves downwardly into contact with the top of the pile. Any overtravel of the means engaging the compression coil spring is taken up by that spring after the feeler has engaged the top of the pile so there is no possibility of binding of parts.

55 While I have referred to a feeler in the singular it is to be understood that the feeler may be multiplied if desired so that a gang of synchronously operable feelers may be employed to engage the top of the pile at different points. However, ordinarily one feeler is sufficient for accomplishment of the purpose.

60 Preferably the connecting member extending from the operating device is connected to an angularly oscillatable member which operates all the parts of the pile governor operating mechanism. The pawl is preferably pivoted to the angularly oscillatable member and that member preferably has a projection adapted to engage the above mentioned compression coil spring to move the feeler downwardly into engagement with the top of the pile. Desirably the compression coil spring is disposed about a rod which extends through a slotted radial projection on the angularly oscillatable member, such projection bearing against the compression coil spring. The rod preferably carries the cam for operating the above mentioned detent. Desirably the pawl has a laterally projecting portion cooperable 65 70 75 with the detent as above explained.

Other details, objects and advantages of the invention will become apparent as the following description of a present preferred embodiment thereof proceeds.

In the accompanying drawings I have shown a present preferred embodiment of the invention in which

Figure 1 is an elevational view from the operator's side of a sheet feeder applied to a printing press, portions of the feeder and press not forming part of the invention claimed being cut away;

Figure 2 is an elevational view of the structure shown in Figure 1 but viewed from the gear side of the press;

Figure 3 is an enlarged fragmentary detail elevational view of a portion of the structure shown in Figure 2, the feed board being shown in operative position;

Figure 3a is a view similar to Figure 3 but showing the feed board in inoperative position;

Figure 4 is an enlarged fragmentary detail vertical cross-sectional view of a portion of the structure shown in Figure 1 and taken on the line IV—IV of Figure 5;

Figure 5 is a fragmentary plan view of a portion of the structure;

Figure 6 is an enlarged vertical transverse cross-sectional view taken on the line VI—VI of Figure 5;

Figure 7 is a more or less diagrammatic fragmentary elevational view showing the feed board in operative and inoperative positions;

Figure 8 is an enlarged vertical longitudinal cross-sectional view taken on the line VIII—VIII of Figure 5;

Figure 9 is an enlarged fragmentary plan view of a portion of the structure;

Figure 10 is a fragmentary elevational view of the structure shown in Figure 9; and

Figure 11 is a fragmentary vertical transverse cross-sectional view taken on the line XI—XI of Figure 10.

Referring now more particularly to the drawings, there is shown apparatus comprising a printing press designated generally by reference numeral 2 and a sheet feeder for feeding sheets one by one to the printing press, the feeder being designated generally by reference numeral 3. The press as shown is of the horizontal flat bed and cylinder type; the press itself may be conventional. The press frame is designated by reference numeral 4 and is mounted in stationary position. The impression cylinder is shown diagrammatically at 5. The impression cylinder turns in the counterclockwise direction viewing Figure 1 and is provided with cylinder grippers for taking one by one the sheets fed thereto by the feeder, each sheet being carried by the impression cylinder for one revolution during which it is pressed against the printing form on the oscillating bed as well known to those skilled in the art. The printed sheet is delivered from the cylinder toward the left viewing Figure 1 in well known manner. Since the present invention is concerned with material handling apparatus illustrated therein as being embodied in a sheet feeder there is no need of showing details of the press and delivery structures and such details have been omitted.

The feeder 3 comprises a frame 6 which carries all the parts of the feeder proper. The feeder frame 6 is pivoted to the press frame 4 by a vertical pivot 7, such pivoting of a feeder frame to a press frame being well known to those skilled

in the art. The pivot 7 in the present case preferably comprises a cylindrical shaft disposed in vertical position and carried by the press frame, the feeder frame having trunnions 8 through which the shaft 7 passes so that the feeder frame may pivot about the shaft 7 by turning of the trunnions 8 on the shaft. The drawings show only the upper portion of the feeder and hence show only the upper trunnion 8. There is also a cooperating lower trunnion carried by the feeder frame 6 through which the shaft 7 passes near the bottom of the feeder.

The shaft 7 is disposed at one side of the press frame, the side at which it is disposed being known to those skilled in the art as the gear side. The opposite side is known as the operator's side. By reason of the pivotal mounting of the feeder upon the press the feeder can be swung laterally to inoperative position about the pivot 7 so as to provide access to the form on the press bed and to the internal portions of the press and feeder. As above indicated, the general type of mounting of the feeder on the press is well known to those skilled in the art. The feeder is maintained in proper elevation relatively to the press by reason of the fact that each of the feeder trunnions 8 bears upon a stationary portion 9 of the press frame. Thus the entire feeder may move as a unit about the axis of the pivot 7 and while so moving remains in fixed vertical position.

The feeder frame 6 has opposed projecting portions 10 in each of which is disposed a flanged bushing 10a fastened to the portions 10 by screws 10b passing through the bushing flanges. A cross shaft 11 is journaled in the bushings 10a. The cross shaft 11 performs an important part in the functioning of the feeder, serving together with the bushings 10a as the horizontal pivot for the feed board and also serving to drive the oscillating carriage along the feed board as will presently be described. The feed board is designated generally by reference numeral 12 and has bearing portions or hubs 12a somewhat offset downwardly, viewing Figures 1 and 6, from the general plane of the feed board through which the bushings 10a and the cross shaft 11 pass whereby the feed board is pivoted to the feeder frame 6 at the portions 10 thereof for turning movement about the axis of the horizontal cross shaft 11. The feed board 12 is pivoted to the cross shaft 11 at its mid-portion, i. e., at the portion of the feed board removed from both ends. The feed board is pivoted to the cross shaft near enough to the longitudinal center of the feed board so that, while it will not ordinarily be exactly balanced about the axis of the shaft 11, it may without great physical effort be turned about the axis of the shaft by the operator or pressman. This may be done manually by taking hold of the feed board and turning it about the axis of the cross shaft. The turning is a virtually instantaneous movement whose accomplishment does not require cranking or operation of any other mechanism. In Figure 7 the feed board is shown in operative position in solid lines and in inoperative position in chain lines. In the other figures except Figure 3a it is shown in operative position; in Figure 3a it is shown in inoperative position. There are two reasons for turning the feed board to the inoperative or chain line position shown in Figure 7. One reason is to permit limited access to the form on the press bed and to the inside of the press. The other reason is to permit disengagement of the feed board from the

press when it is desired to swing the feeder as a whole about the vertical pivot 7 to inoperative out of the way position to permit full access to the form on the press bed and to the interior of the press and feeder. When the feed board 12 is in operative position its left-hand end viewing Figure 1 engages the press as will presently appear, so the feed board should be moved to the more nearly vertical inoperative position shown in chain lines in Figure 7 when the feeder is to be swung about the vertical pivot 7 to inoperative position.

The feed board when in its generally horizontal operative position has somewhat more of its mass disposed to the left of the axis of the shaft 11 viewing Figure 1 than to the right of such axis; hence the feed board is somewhat overbalanced so that its normal tendency is to turn in the counterclockwise direction about the axis of the shaft 11 viewing Figure 1. The amount by which it is out of balance is not great enough to impose great difficulty in manual turning of the feed board between operative and inoperative positions. Nevertheless it is desirable to employ means acting on the feed board assisting in raising the heavier end thereof when the feed board is turned from operative to inoperative position and cushioning the return of the feed board from inoperative to operative position. Pivoted to each of the opposed downwardly projecting portions of the feed board at 12b is a rod 12c which passes through a guiding bore 12d in a stud 12e pivoted to the inside of the corresponding feeder frame portion 10 as shown in Figure 1. A compression coil spring 12f is disposed between the connection of each rod 12c to the feed board and the stud 12e. When the feed board is in operative position the springs 12f are compressed. When the feed board is turned about the axis of the shaft 11 to inoperative position the springs 12f counteract to a desired extent the overbalance of the feedboard and facilitate the turning. As the feed board approaches vertical position the overbalance diminishes as does also the effect of the springs 12f since by reason of the fact that the pivots 12b are moving generally toward the left viewing Figure 1 away from the studs 12e the spring 12f are allowed to expand. When the feed board is turned back from inoperative to operative position the springs 12f cushion its movement, becoming progressively more and more effective as the feed board nears operative position until they attain their maximum effectiveness when operative position is reached.

The feed board has near its end which cooperates with the impression cylinder 5 lugs 12g threadedly receiving screws 12h, each of which is maintained in desired adjusted position by a nut 12i. The screws 12h project from the bottoms of the lugs 12g and when the feed board settles into operative position enter sockets 12j formed to receive them in the press frame. The screws 12h thus accurately position the feed board relatively to the press frame and hence relatively to the impression cylinder and cooperate with the locking means presently to be described to maintain the feed board accurately positioned. By reason of their entry into the sockets 12j the screws prevent undesired lateral movement or skewing of the feed board.

A carriage is carried by and oscillates along the feed board to effect the feeding of sheets one by one to the impression cylinder 5. The carriage itself may be conventional. It is shown

in the drawings at 13 but is not illustrated in detail because the specific mechanism of the carriage does not constitute the present invention. The carriage is mounted in guides on the feed board to oscillate back and forth along the feed board generally in the plane of the feed board as known to those skilled in the art. The carriage has on its bottom two downwardly facing racks 14 each meshing with a pinion 15 fastened to the shaft 11. The racks 14 are positioned at opposite sides of and preferably substantially equidistant from the center line of the carriage. Means presently to be described are provided for oscillating the shaft 11 and since each pinion 15 is fixed to the shaft 11 and must turn therewith and is at all times in mesh with the corresponding rack 14 oscillation of the shaft 11 causes oscillatory movement of the carriage 13 along the feed board.

The carriage 13 is equipped with means well known to those skilled in the art for advancing sheets one by one along the feed board from the top of the pile of sheets in the feeder to the impression cylinder where each sheet is side and front registered to the impression cylinder and taken from registry by the cylinder grippers. All this is standard feeder structure and hence is not shown in detail. An effort has been made to eliminate from the drawings as many parts as possible which do not constitute the invention herein claimed. The means on the carriage for advancing the sheets one by one along the feed board may be pneumatic means. For example, there may be two sets of suckers on the carriage, one at each end of the carriage. The set of suckers at the feeder end of the carriage may take a sheet from other suckers which lift it from the top of the pile and upon movement of the carriage toward the impression cylinder feed that sheet to a position about half way along the feed board where the sheet may be released by the suckers on the carriage and retained by stationary suckers in the feed table 12k which is the sheet supporting portion of the feed board. The carriage may then move back toward the feeder end of the feed board and upon the succeeding motion toward the impression cylinder the suckers on the end of the carriage nearer the impression cylinder may take the sheet from its intermediate position on the feed table and deliver it to a point of registry at the front or cylinder end of the feed board; after the sheet is front and side registered the sheet is taken from the feed board by the cylinder grippers. This type of sheet handling in a sheet feeder is known to those skilled in the art.

A manually operated latch pin 16 is provided in the feeder frame 6 at the operator's side to hold the feed board in uptilted or inoperative position as shown in chain lines in Figure 7. The latch pin may be spring pressed inwardly so that when the feed board moves to inoperative position a cam on the feed board may depress the pin outwardly until a portion of the feed board has passed the pin whereupon the pin may be released to be projected inwardly by its spring to positively hold the feed board against turning back to operative position until the latch pin is manually pulled out by the operator. Thus at the will of the operator the feed board can be latched in inoperative position but by a simple manual operation of pulling out the latch pin the feed board can be released for turning movement back to operative position, which turning movement, as above indicated, can be effected

in a virtually instantaneous manual operation due to the fact that the feed board is mounted to turn about the axis of the shaft 11 at its mid-portion.

The press frame 4 has a portion 17 projecting toward the feeder, such portion having an underside 18 with which the upper end of an adjustable screw 19 is adapted to engage, the screw 19 being maintained by a nut 20 in adjusted position in the end of a hook-shaped arm 21 fixed to a cross shaft 22 journaled in the feed board 12. The shaft 22 extends across the feed board from side to side of the feeder and at the operator's side has fixed to it a handle 23 whereby the operator may turn the shaft 22 between a position in which the feed board is locked to the press as shown in solid lines in Figures 1-4 and 7 and a position in which the arm 21 is turned in the counterclockwise direction from the position in which it is shown in Figure 4 so as to be out of contact with the portion 17 of the press frame; such position of the arm 21 is shown in chain lines in Figure 7 and in solid lines in Figure 3a. Movement of the arm 21 to the inoperative or chain line position of Figure 7 and solid line position of Figure 3a unlocks the feed board from the press so that the feed board may be swung up to inoperative position.

Fixed to the shaft 22 is an arm 24 to the outer end of which is pivoted at 25 a rod 26 extending toward the feeder end of the apparatus and having a hook-shaped end 27. The rod 26 passes through an opening provided therefor in a guide member 28 pivoted in the side of the feed board. When the feed board is locked to the press as shown in Figure 4 the arm 24 holds the hook 27 in a position relatively close to the feeder end of the apparatus in which the hook 27 is inoperative. While the hook is disposed in the plane of the path of the carriage along the feed board it is positioned beyond the end of the path of the carriage in its movement toward the feeder end of the apparatus and hence can have no function. When, however, the shaft 22 is turned through approximately half a revolution from the position in which the feed board is locked to the press to the position indicated in chain lines in Figure 7 and in solid lines in Figure 3a in which the feed board is unlocked the arm 24 causes movement of the hook 27 to the left viewing Figure 4 so that it intercepts the carriage if the carriage moves toward the feeder end of the apparatus. When in that position the hook 27 positively prevents the carriage, when the feed board is turned up to the chain line position of Figure 7 and the solid line position of Figure 3a, from striking the pile of sheets in the feeder; in other words, the hook limits the extent to which the carriage can move when the feed board is turned so that gravity tends to move the carriage toward the feeder end of the apparatus. Were it not for the hook 27 the carriage would strike the pile of sheets in the feeder when moving the feed board to upright position. The hook 27 is resilient and when the carriage moves toward the feeder end of the apparatus a transverse member on the carriage is pressed into the hook, which yields slightly to permit the stud to enter it. Thereafter the hook not only positively prevents the carriage from moving toward the feeder end of the apparatus far enough to strike the pile of sheets in the feeder but also by its resilient action holds the carriage against movement toward the press. Thus the hook 27 which is automatically moved to operative position when the

feed board is unlocked from the press serves to hold the carriage against undesired movement due to gravity in either direction along the feed board. Nevertheless the carriage can be disengaged from the hook by the operator by simply moving the carriage toward the end of the feed board nearer the impression cylinder whereby to release the member 27a from the resilient grip of the hook thereon. When the feed board is again locked to the press the hook 27 is moved out to its inoperative position as shown in Figure 4 where it is disposed beyond the end of the path of the portion of the carriage which is adapted to engage with the hook when the latter is in its operative position.

Fastened to the extremity of the shaft 22 which is disposed at the gear side of the feeder is a sleeve 29 from which projects an arm 30 generally parallel to the axis of the shaft 22, the outer extremity of the arm 30 being turned inwardly at right angles to and intersecting the axis of the shaft 22 as shown at 31. The portion 31 has therein a slot 32 which is elongated transversely of and intersects the axis of the shaft 22. A pin in the front of a bolt 33 is disposed in the slot 32 and is adapted for movement along the slot as will presently be described. The bolt 33 also passes through a circular bore 34 in the longer arm of an L-shaped member 35 whose shorter arm is fastened at 36 to a rod 37 pivoted at 38 to an arm 39 of a bell crank lever 40 pivoted at 41 to a bracket 42 forming part of the feed board. The other arm 43 of the bell crank lever 40 carries at its extremity a hub 44 within which is disposed a pin 45 which rides in a peripheral groove 46 formed in a pinion 47 mounted on the shaft 11 for both free turning movement and sliding movement along the shaft. Keyed to the shaft 11 at 48 and also held against movement axially of the shaft is an inside gear 49 with which the pinion 47 is adapted to mesh when moved toward the right to the position shown in Figure 6. The pinion has a bore 50 parallel to its axis but disposed at one side thereof into which a pin 51 is driven and the inside gear 49 has a bore 52 which guidingly receives the pin 51 when the pinion 47 is moved toward the inside gear 49. The pin 51 rides around the surface 53 of the inside gear 49, which surface is intersected by the bore 52, until the pin 51 enters the bore 52 whereupon the pinion 47 is permitted to move into mesh with the inside gear 49. The function of the pin 51 is to insure that when the pinion 47 moves into mesh with the inside gear 49 it will do so in proper timed relationship so that the carriage will be operated in proper cooperative relationship with other elements of the apparatus. The outer end of the shaft 11 is journaled in a bearing 54 disposed within a hub 55 forming a portion of the feeder frame 6, another portion of which is shaped as a hood 56 covering the pinion 47 and the inside gear 49.

Projecting from the feed board 12 at the gear side of the apparatus is a pin 57 to which is fastened one end of a tension coil spring 58, the other end of which is connected with the bottom of the pivot pin 38. The spring 58 tends at all times to turn the bell crank lever 40 in the counterclockwise direction viewing Figure 5 about the axis of the pivot 41.

When the shaft 22 is in the position which it occupies when the feed board 12 is locked to the press the member 29-30-31 is in the position shown in Figure 5 and the spring 58 maintains the bell crank lever 40 in the position shown in

Figures 5 and 6 in which the pin 45 operating in the annular groove 46 of the pinion 47 maintains the pinion 47 in mesh with the inside gear 49. When, however, the shaft 22 is turned through approximately half a revolution to the position in which the feed board is unlocked from the press the member 29-30-31 is likewise turned through approximately half a revolution with the result that the pin 33 is moved toward the left viewing Figure 5 by engagement therewith of the end of the slot 32 nearest the portion 30. Due to such movement the rod 37 is moved toward the left viewing Figure 5 and the bell crank lever 40 is turned in the clockwise direction about the axis of the pivot 41 against the action of the spring 58 to withdraw the pinion 47 toward the left viewing Figure 6 out of mesh with the inside gear 49. Thus when the feed board is locked to the press the spring 58 is free to move the pinion 47 into mesh with the inside gear 49 and maintain it in mesh therewith while when the feed board is unlocked from the press the pinion 47 is withdrawn from mesh with the inside gear 49. The slot 32 is elongated to prevent binding of the parts upon locking of the feed board to the press. As will presently be described, the pinion 47 partakes of constant oscillatory movement and if the slot 32 were not elongated there would be danger of damage to the parts upon turning of the shaft 22 which would force the pinion 47 against the inside gear 49. Since the pinion 47 can only move into mesh with the inside gear 49 when the pin 51 enters the bore 52 it is important that the force urging the pinion into mesh with the inside gear be a resilient rather than a positive force. The resilient force is supplied by the spring 58, the function of the member 29-30-31 with the elongated slot 32 therein being to permit the spring 58 to move the pinion 47 toward the right viewing Figure 6 into mesh with the inside gear 49.

It is important that when the feed board is in its upright position as shown in chain lines in Figure 7 the pinion 47 be maintained out of engagement with the inside gear 49 even though the shaft 22 be turned to the position of Figure 5. To this end there is fastened to the feeder frame a stop member 59 which is stationarily disposed in position so that when the feed board 12 is turned up to inoperative position the arm 39 of the bell crank lever 40 will engage the stop member 59, which member will by engagement with the arm 39 positively hold the pinion 47 out of mesh with the inside gear 49 regardless of the position to which the shaft 22 may be turned. In other words, the stop member 59 renders inoperative the spring 58 to move the pinion 47 into mesh with the inside gear 49 when the feed board is in upright position. When the feed board is moved back to operative position the arm 39 moves away from the stop member 59, allowing the spring 58 to become operative to urge the bell crank lever 40 to turn in the counterclockwise direction viewing Figure 5.

The shaft 22 has a radial lug 22a to which is pivoted at 22b a rod 22c passing through a slot 22d in a stud 22e pivotally mounted in a lug 22f integral with and projecting downwardly from the feed board 12. A compression coil spring 22g bears between the connection of the rod 22c with the lug 22a and the stud 22e. Thus there is provided an overcenter holding device resiliently acting on the shaft 22 to hold it in each of its two positions as clearly shown in Figure 7.

Another stop member 60 is threaded into the

feed board at 61 and carries an adjustable stop screw 62 maintained in adjusted position by a nut 63 adapted to engage the outer end of the arm 39 of the bell crank lever 40 when the pinion 47 has been moved into mesh with the inside gear 49 to relieve the inside gear 49 of substantial axial thrust by the pinion 47. In other words, the thrust is taken by non-rotating means instead of by rotation means so that no substantial wear is occasioned thereby.

By reason of the provision of the annular groove 46 in the pinion 47 the pin 45 rides in that groove at all times regardless of the angular position of the feed board 12 about the axis of the shaft 11. In other words, the operating means for the pinion 47 remains continuously in engagement in all angular positions of the feed board about the axis of the shaft 11.

Disposed about the vertical shaft 7 above the upper trunnion 8 is a hollow circular rack 64. The rack 64 is in the form of a sleeve mounted on the shaft 7 for guided movement parallel to the axis of that shaft. At its lower end the rack 64 has a sleeve portion 65 having therein an outwardly facing annular groove 66. Surrounding the sleeve portion 65 is a driving member 67 through which pass bolts 68 which enter the annular groove 66. The driving member 67 has two spaced apart outwardly projecting lugs 69 to which is pivoted at 70 a link 71 having its upper end disposed between the lugs 69 connected with a crank motion driven from the press drive, the crank motion being conventional and hence not being shown in detail. Driving of the press operates the crank motion to cause the link 71 to oscillate the circular rack 64 up and down on the vertical shaft 7. The circular rack 64 is at all times in mesh with the pinion 47 so that during operation of the apparatus the circular rack is continuously moving up and down and the pinion 47 is continuously oscillating angularly about the axis of the shaft 11. The pinion 47 may while so oscillating be moved along the axis of the shaft 11 as above described. Thus the connection from the press drive to the feeder for oscillating the feeder carriage is maintained at all times, the means for moving the pinion 47 axially of the shaft 11 being the control means determining whether or not at any particular time the feeder carriage is oscillated. As above explained, the control means remains operable when the feed board is tilted since tilting of the feed board simply moves the pin 45 around the annular slot 46.

When the feeder is swung out to inoperative position about the axis of the shaft 7 the pinion 47 remains in mesh with the circular rack 64, moving bodily about the axis of the shaft 7 at the same time. Consequently even swinging of the feeder out to inoperative position does not disengage the connection from the press drive for operating the feeder carriage.

Disposed about the circular rack 64 just above the driving member 67 is a collar 72 which is constrained to move up and down with the circular rack 64, but as will presently be described, turns relatively thereto when the feeder is swung out about the axis of the shaft 7 to inoperative position. A rod 73 is pivoted at 74 to a lever 75 and extends downwardly through an eye 76 in the collar 72 and thence through a guiding bore 77 in the feeder frame. Collars 78 are fastened to the rod 73 immediately above and below the collar 72. Thus up and down movement of the circular rack 64 causes up and down movement

of the rod 73. When the feeder is swung out to inoperative position about the axis of the shaft 7 the rod 73 causes the collar 72 to turn about the circular rack 64.

The lever 75 has a hub portion 79 through which passes a shaft 80. The lever 75 is freely turnable upon the shaft 80. The shaft 80 is journaled in the feeder frame and has keyed thereto two worms 81 of opposite hand. Each of the worms 81 meshes with a worm wheel 82. Each worm wheel 82 is keyed to a longitudinal shaft 83, one of the shafts 83 being adjacent one side of the feeder and the other being adjacent the opposite side of the feeder. Thus turning of the shaft 80 turns the two shafts 83 but in opposite directions.

Keyed to each shaft 83 are two sprockets 84. An endless sprocket chain 85 is trained about and depends from each of the four sprockets 84. The pile support 86 has spaced apart downwardly projecting ribs 87 so that when it is set down on the floor the peel of a carrier truck may be projected beneath the body of the pile support to lift it and carry it about. The pile support 86 is fastened to each of the four chains 84 at the inside reach thereof. The manner of fastening of the pile support to the chains does not constitute the present invention but may be conventional and hence is not shown in detail.

Thus when the shaft 80 is turned in one direction the pile support is raised and when the shaft 80 is turned in the opposite direction the pile support is lowered.

Keyed to the shaft 80 is a ratchet 88. The ratchet is arranged on the shaft in such relation to the worms 81 that when the shaft 80 is turned in the clockwise direction viewing Figure 10 the pile support 86 is raised.

An integral projection 89 extends out radially from the hub 79 and has journaled in its outer end at 90 a short shaft 91 which at one end has fixed thereto a pawl 92 disposed directly above the ratchet 88 and at the other end has fixed thereto a follower member 93 comprising a curved neck portion 94 and an elongated operating portion 95. The operating portion 95 has a lateral projection 96 projecting from the operating portion 95 in a direction away from the pawl 92.

An integral projection 97 extends out radially from the hub 79 and has therein an elongated slot 98. The left-hand face of the projection 97 viewing Figure 10 is curved to act as a cam. A rod 99 is disposed generally horizontally and passes through the slot 98 in the projection 97. The rod 99 is adjacent one end guided in a guide 100 fixed to the feeder frame and is at its other end pivotally connected by a pin 101 to a pair of spaced apart generally downwardly projecting arms 102 fixed to a shaft 104 mounted for rotation in the feeder frame. A generally horizontally extending arm 105 is also fixed to the shaft 104. Pivoted to the arm 105 at 106 is a downwardly projecting feeler 107 whose lower extremity is adapted to engage the top of a pile of sheets on the pile support 86. The feeler 107 is guided within a guide 108 carried by the feeder frame. Thus axial oscillation of the rod 99 causes generally vertical oscillation of the feeler 107.

Fixed to the rod 99 is a collar 109 against which bears a compression coil spring 110, the opposite end of which bears against a washer 111 which lies against the cam face of the projection 97. A pin 112 extends through the rod 99 and serves to limit the extent to which the spring 110 may expand. A tension coil spring 113 is fas-

tened at one end to a stud 114 carried by the feeder frame and at the other end to a stud 103 threaded into the pin 101 and tends to raise the feeler 107 upwardly out of contact with the top of the pile of sheets on the pile support 86.

Pivoted to the feeder frame at 115 is a detent 116 having an operating portion 117 normally disposed beneath the portion 96 of the member 93 as shown in Figure 11. The detent 116 is of generally inverted L-shape, extending upwardly and then laterally from the pivot 115. In the laterally or generally horizontally extending portion of the detent 116 is threaded a screw 118 maintained in adjusted position by a nut 119. The screw projects downwardly from the detent. A cam 120 is fixed to the rod 99 and is positioned thereon so that when the rod 99 moves toward the left viewing Figure 10 a predetermined distance it will engage the bottom of the screw 118 and then cam the detent 116 to turn in the counterclockwise direction about the pivot 115 viewing Figure 11 until the portion 117 moves out of the path of the portion 96 of the follower member 93 which permits the pawl 92 to drop into engagement with the ratchet 88. The rod 99 also has fixed thereto a stop member 121 which limits movement of the rod 99 toward the right viewing Figure 10 by engagement with the guide 100.

The operation of the pile governor will now be described. The lever 75 partakes of continuous angular oscillation during operation of the apparatus. Normally the portion 117 of the detent 116 lies beneath the portion 96 of the follower member 93 so that as the lever 75 oscillates, the follower member 93, being itself held up by the portion 117 of the detent, in turn holds the pawl 92 out of operative engagement with the ratchet 88. Viewing Figure 10, as the follower member 93 moves toward the right in clockwise angular movement about the axis of the shaft 80 the under surface of the portion 96 thereof rides atop the portion 117 of the detent 116 which maintains the pawl 92 out of operative engagement with the ratchet 88. However, at the end of the angular oscillatory movement toward the right viewing Figure 10 of the follower member 93 the left-hand extremity of the portion 96 passes beyond the portion 117 of the detent and at that time the pawl 92, having passed two teeth of the ratchet, is permitted to come into engagement with the ratchet beyond the second passed tooth, but such engagement is not operative engagement as the pawl does not have any effect on the ratchet. It is, however, important that at the end of the angular oscillatory movement toward the right viewing Figure 10 of the follower member 93 the portion 96 thereof pass beyond the portion 117 of the detent 116 so that upon the return movement toward the left of the follower member 93 the portion 96 will always ride up on the portion 117 regardless of whether or not the portion 117 has been beneath and in operative engagement with the portion 96 during the previous angular oscillation of the follower member 93 toward the right.

Thus ordinarily the pawl 92 is held out of operative engagement with the ratchet 88 and simply partakes of constant oscillation about the axis of the shaft 80 without performing any function.

The spring 113 urges the feeler 107 upwardly out of engagement with the top of the pile of sheets on the pile support 86. Upward movement of the feeler 107 is limited by engagement of the stop member 121 with the guide 100. When the lever 75 is at the extreme clockwise end of its

angular oscillation about the axis of the shaft 80 viewing Figure 10 the projection 97 has moved toward the right from the position in which it is shown in Figure 10 so that pressure on the spring 110 has been relieved sufficiently to permit the spring 113 to raise the feeler 107, and the rod 99 is in its extreme right-hand position with the stop member 121 against the guide 100 and the right-hand end of spring 110 and the washer 111 are stopped by the pin 112. On the succeeding counterclockwise oscillatory movement of the lever 75 the projection 97 compresses the spring 110. Compression of the spring 110 continues until the force exerted thereby against the rod 99 through the collar 109 thereon overcomes the action of the spring 113, whereupon the feeler 107 is moved downwardly into engagement with the top of the pile. Any overtravel of the projection 97 after the feeler 109 has engaged the top of the pile is taken up by further compression of the spring 110.

When the top of the pile is within the operative height range so that raising of the pile to maintain its top within that range is not immediately necessary engagement of the feeler with the top of the pile stops movement of the rod 99 toward the left viewing Figure 10 before the cam 120 fastened to the rod 99 comes into engagement with the bottom of the screw 118. Thus nothing is done to remove the portion 117 of the detent 116 from beneath the portion 96 of the follower member 93 and the feeler 107 and the rod 99 merely oscillate without turning the shaft 80.

When enough sheets have been removed from the pile that raising of the pile to bring its top into the operative height range is indicated the feeler 107 moves down far enough before engaging the top of the pile that the cam 120 engages the bottom of the screw 118 and tilts the detent 116 so that the detent turns in the counterclockwise direction about the pivot 115 viewing Figure 11. Such tilting of the detent 116 at first slightly raises the follower member 93 until the portion 117 of the detent clears the edge of the portion 96 of the follower member whereupon the follower member drops down. Since the pawl 92 is rigidly connected with the follower member by means of the short shaft 91 so as to be in effect integral therewith the pawl 92 likewise drops down (i. e., turns in the clockwise direction about the axis of the shaft 91 viewing Figure 10) until it comes into operative engagement with the ratchet 88. This always happens when the lever 75 is at the extreme counterclockwise extremity of its angular oscillation about the axis of the shaft 80 viewing Figure 10 since it is only at that time that the cam 120 can engage the bottom of the screw 118. As soon as the lever 75 commences the next clockwise oscillatory movement viewing Figure 10 the cam 120 immediately moves out of contact with the bottom of the screw 118 permitting the detent 116 to turn back in the clockwise direction about the pivot 115 viewing Figure 11 until the lower right-hand corner of the portion 117 viewing Figure 11 engages the side of the follower member 93 which it will be remembered has dropped down to permit the pawl 92 to operatively engage the ratchet 88. As clockwise movement of the lever 75 viewing Figure 10 continues the pawl 92 which is in operative engagement with the ratchet 88 turns the shaft 80 in the clockwise direction viewing Figure 10. The shaft 80 through the worms 81 and the worm wheels 82 turns the shafts 83 outwardly to raise the inner reaches of the chains 85 and hence move the pile support 86

upwardly through an increment of movement. As the lever 75 reaches the clockwise extremity of its angular oscillatory movement viewing Figure 10 the portion 117 of the detent 116, which has been riding with the detent in slightly tilted position along the side face of the follower member 93, passes beyond the end of the portion 96 of the follower member 93 so that upon the succeeding counterclockwise movement of the lever 75 the portion 117 again moves under the portion 96 and raises the follower member 93. Thus upon each counterclockwise movement of the lever 75 viewing Figure 10 the portion 117 of the detent 116 is always beneath the portion 96 of the follower member 93 and holds up the follower member and the pawl 92. Turning of the detent 116 in the clockwise direction about the pivot 115 is limited by engagement of a pin 122 in the side of the detent with the head 123 of a screw 124 in the feeder frame serving as a stop member. The screw 124 is maintained in adjusted position by a nut 125.

A hand crank 126 has a hub 127 through which the shaft 80 passes. The shaft 80 has a pin 128 extending therethrough and projecting both upwardly and downwardly therefrom and the hub 127 has opposed lateral recesses or pockets 129 therein adapted to receive the projecting ends of the pin 128 when the crank 126 is moved toward the left viewing Figure 11 or upwardly viewing Figure 9. The crank 126 is maintained on the shaft 80 but is allowed sufficient freedom of movement axially of the shaft to be moved into and out of engagement with the pin 128 by a stop pin 130. The crank 126 is used for manually raising or lowering the pile support. The pile support may be raised by the crank 126 at any time and may be lowered by the crank 126 at any time except when the pawl 92 is in operative engagement with the ratchet 88.

The feeder is equipped with the usual side registering or side guiding means operated by the usual transversely oscillatable rod 131 which in turn is oscillated by the usual three-armed lever 132. Projecting from the rod 131 is a pin 133 received within a yoke 134 in the end of one arm 135 of the lever 132. The lever 132 is pivoted to the feed board at 136. Oscillation of the lever 132 about the pivot 136 oscillates the rod 131 transversely of the feed board to side register the sheets in well known manner. Since the side registering means per se do not constitute the present invention such means are not shown in detail.

The lever 132 is oscillated by a link 137. When the sheets are to be registered to one side of the feed board the link 137 is pivotally connected to the second arm 138 of the three-armed lever 132 while when the sheets are to be registered to the other side of the feed board the link 137 is pivotally connected to the third arm 139 of the three-armed lever 132; this is standard feeder structure.

However, improved means are provided for oscillating the link 137. That link is pivoted at 140 to an upwardly projecting arm 141 of a bell crank lever 142 pivoted to the feed board at 143. The lower arm 144 of the bell crank lever 142 carries a follower 145 which extends through an opening 145a in the feed board 12 and operates in a cam groove 146 in the outside face of the carriage oscillating pinion 15 or if there be two such pinions the one disposed at the gear side 75 of the feeder. This provides an extremely simple

and effective means for operating the side registering or side guiding mechanism.

While I have shown and described a present preferred embodiment of the invention it is to be distinctly understood that the invention is not limited thereto but may be otherwise variously embodied within the scope of the following claims.

I claim:

1. Material handling apparatus comprising a feeler, an angularly oscillatable operating member, a connection from the operating member to the feeler oscillating the feeler between a downward position in engagement with the top of a pile of material whose height changes during operation of the apparatus and an upward position above and out of engagement with the top of the pile, said connection including a slotted projection on the operating member and an oscillatable rod having a portion lying within the slot yieldably operated by said projection upon angular oscillation of the operating member, the amplitude of oscillation of the rod varying with the elevation of the top of the pile, pile moving means for changing the elevation of the pile to compensate for its change in height and maintain its top at approximately a fixed elevation, a connection from the operating member to the pile moving means, means normally maintaining the second mentioned connection inoperative, the rod having thereon a cam, and means operated by the cam in a predetermined range of amplitude of oscillation of the rod displacing the last mentioned means whereby to render operative the second mentioned connection to move the pile.

2. Material handling apparatus comprising a feeler, an angularly oscillatable operating member, a connection from the operating member to the feeler oscillating the feeler between a downward position in engagement with the top of a pile of material whose height changes during operation of the apparatus and an upward position above and out of engagement with the top of the pile, said connection including a movable support for the feeler, a projection on the operating member and an oscillatable rod operated by said projection upon angular oscillation of the operating member and connected with the feeler support, spring means acting on the feeler support urging the feeler support to a position in which the feeler is in its upward position and spring means interposed between a portion of the rod and the projection through which the projection moves the rod upon angular movement of the operating member in one direction to temporarily overcome the action of the first mentioned spring means and move the feeler support to a position in which the feeler is in its downward position, the amplitude of oscillation of the rod varying with the elevation of the top of the pile, pile moving means for changing the elevation of the pile to compensate for its change in height and maintain its top at approximately a fixed elevation, a connection from the operating member to the pile moving means and means operated by the rod in a predetermined range of amplitude of oscillation of the rod rendering the second mentioned connection operative to move the pile.

3. Material handling apparatus comprising a feeler, an oscillatable operating member, a connection from the operating member to the feeler oscillating the feeler between a downward position in engagement with the top of a pile of material whose height changes during operation of the apparatus and an upward position above and

out of engagement with the top of the pile, said connection including a movable support for the feeler and an actuating member operated by the operating member upon oscillation of the operating member and connected with the feeler support, spring means acting directly on the feeler support urging the feeler support to a position in which the feeler is in its upward position and spring means interposed between a portion of the actuating member and the operating member through which the operating member moves the actuating member upon movement of the operating member in one direction to temporarily overcome the action of the first mentioned spring means and move the feeler support to a position in which the feeler is in its downward position, the amplitude of oscillation of the actuating member varying with the elevation of the top of the pile, pile moving means for changing the elevation of the pile to compensate for its change in height and maintain its top at approximately a fixed elevation, a connection from the operating member to the pile moving means and means operated by the actuating member in a predetermined range of amplitude of oscillation of the actuating member rendering the second mentioned connection operative to move the pile.

4. Material handling apparatus comprising a feeler, a generally vertically oriented carrier for the feeler, a guide for the carrier through which the carrier is adapted to move during upward and downward movements of the feeler, an oscillatable operating member, a connection from the operating member to the feeler carrier oscillating the same between a downward position in which the feeler is in engagement with the top of a pile of material whose height changes during operation of the apparatus and an upward position in which the feeler is above and out of engagement with the top of the pile, said connection including an actuating member operated by the operating member upon oscillation of the operating member and connected with the feeler carrier, spring means urging the feeler carrier to its second mentioned position and spring means interposed between a portion of the actuating member and the operating member through which the operating member moves the actuating member upon movement of the operating member in one direction to temporarily overcome the action of the first mentioned spring means and move the feeler carrier to its first mentioned position, the amplitude of oscillation of the actuating member varying with the elevation of the top of the pile, pile moving means for changing the elevation of the pile to compensate for its change in height and maintain its top at approximately a fixed elevation, a connection from the operating member to the pile moving means and means operated by the actuating member in a predetermined range of amplitude of oscillation of the actuating member rendering the second mentioned connection operative to move the pile.

5. Material handling apparatus comprising two material handling portions, a pivot pivotally connecting said portions together, an operating member mounted on the pivot for movement axially of the pivot, one of the material handling portions having a support for a pile of material whose height changes during operation of the apparatus, pile moving means for changing the elevation of the pile to compensate for its change in height and maintain its top at approximately a fixed elevation and a driving connection be-

tween the operating member and the pile moving means effective upon movement of the operating member axially of the pivot to operate the pile moving means.

6. In a press, a main frame, a printing or like couple carried by the main frame, a feeder, a pivot pivotally connecting the feeder to the main frame of the press, an operating member mounted on the pivot for movement axially of the pivot, the feeder having a support for a pile of sheets, means for removing sheets from the pile to the couple and thereby decreasing the height of the pile of sheets, means for elevating the pile support with the pile thereon to compensate for loss of height of the pile due to removal of sheets and maintain the top of the pile at approximately a fixed elevation and a driving connection between the operating member and the pile support elevating means effective upon movement of the operating member axially of the pivot to operate the pile support elevating means.

7. In a press, a main frame, a printing or like couple carried by the main frame, a feeder, a pivot pivotally connecting the feeder to the main frame of the press so that the feeder may be swung about the axis of the pivot between operative and inoperative positions, an operating member slidably axially of the pivot, the feeder having a support for a pile of sheets, means for removing sheets from the pile to the couple and thereby decreasing the height of the pile of sheets, means for elevating the pile support with the pile thereon to compensate for loss in height of the pile due to removal of sheets and maintain the top of the pile at approximately a fixed elevation and a driving connection between the operating member and the pile support elevating means effective upon sliding of the operating member axially of the pivot to operate the pile support elevating means, the operating member and the driving connection turning with the feeder about the axis of the pivot when the feeder is swung between operative and inoperative positions.

8. In a press, a main frame, a printing or like couple carried by the main frame, a feeder, a pivot pivotally connecting the feeder to the main frame of the press so that the feeder may be swung about the axis of the pivot between operative and inoperative positions, an operating member movable axially of the pivot, the feeder having a support for a pile of sheets, means for moving sheets from the pile to the couple and thereby decreasing the height of the pile of sheets, means for elevating the pile support with the pile thereon to compensate for loss in height of the pile due to removal of sheets and maintain the top of the pile at approximately a fixed elevation and a driving connection between the operating member and the pile support elevating means effective upon movement of the operating member axially of the pivot to operate the pile support elevating means, the driving connection including a rod extending generally upwardly from the operating member to the pile support elevating means, the feeder having a guide for the rod to maintain it in proper orientation relatively to the pile support elevating means in all positions of the feeder relatively to the press, the rod turning the operating member about the axis of the pivot when the feeder is swung between operative and inoperative positions.

9. Material handling apparatus comprising two material handling portions, a pivot pivotally connecting said portions together, an operating de-

vice mounted on the pivot for movement axially of the pivot, one of the material handling portions having a support for a pile of material whose height changes during operation of the apparatus, 5 pile support moving means for changing the elevation of the pile to compensate for its change in height and maintain its top at approximately a fixed elevation and oscillatable material handling means handling the material sequentially relatively to its disposal in the pile, a driving connection between the operating device and the pile support moving means effective upon movement of the operating device axially of the pivot to operate the pile support moving means and a driving 10 connection between the operating device and the oscillatable material handling means effective upon movement of the operating device axially of the pivot to oscillate the oscillatable material handling means.

10. Material handling apparatus comprising a frame, a pivot for the frame about the axis of which the frame is swingable, an operating device mounted on the pivot for movement axially of the pivot, a support for a pile of material whose height changes during operation of the apparatus 25 mounted on the frame, pile support moving means for changing the elevation of the pile to compensate for its change in height and maintain its top at approximately a fixed elevation also mounted on the frame, oscillatable material handling means handling the material sequentially relatively to its disposal in the pile also mounted on the frame, a driving connection between the operating device and the pile support moving means 30 effective upon movement of the operating device axially of the pivot to operate the pile support moving means and a driving connection between the operating device and the oscillatable material handling means effective upon movement of the 35 operating device axially of the pivot to oscillate the oscillatable material handling means.

11. Material handling apparatus comprising a frame, a pivot for the frame about the axis of which the frame is swingable, an operating device 45 mounted on the pivot for movement axially of the pivot, the operating device having a portion non-turnable about the axis of the pivot when the frame is swung thereabout and a portion turnable about the axis of the pivot when the frame is swung thereabout, a support for a pile of material whose height changes during operation of the apparatus mounted on the frame, pile support moving means for changing the elevation of the pile to compensate for its change in height and maintain its top at approximately a fixed elevation 50 also mounted on the frame, oscillatable material handling means handling the material sequentially relatively to its disposal in the pile also mounted on the frame, a driving connection between the second mentioned portion of the operating device and the pile support moving means effective upon movement of the operating device axially of the pivot to operate the pile support moving means and a driving connection between the first mentioned portion of the operating device 55 and the oscillatable material handling means effective upon movement of the operating device axially of the pivot to oscillate the oscillatable material handling means.

12. Material handling apparatus comprising a frame, a pivot for the frame about the axis of which the frame is swingable, a sleeve disposed about the pivot and movable axially of the pivot but non-turnable about the axis of the pivot when the frame is swung thereabout, an operating 60

member movable axially of the pivot with the sleeve, a support for a pile of material whose height changes during operation of the apparatus mounted on the frame, pile support moving means for changing the elevation of the pile to compensate for its change in height and maintain its top at approximately a fixed elevation also mounted on the frame, oscillatable material handling means handling the material sequentially relatively to its disposal in the pile also mounted on the frame, a driving connection between the operating member and the pile support moving means effective upon movement of the operating member axially of the pivot to operate the pile support moving means and a driving connection between the sleeve and the oscillatable material handling means effective upon movement of the sleeve axially of the pivot to oscillate the oscillatable material handling means, the first mentioned driving connection turning the operating member about the axis of the pivot when the frame is swung thereabout.

13. Article handling apparatus comprising a feeler, oscillatable operating means, a connection from the operating means to the feeler oscillating the feeler between a position in engagement with the end of a series of articles to be fed seriatim, the location of which end of the series of articles changes during operation of the apparatus, and a position out of engagement with said end of the series of articles, the amplitude of oscillation of the connection varying with the location of said end of the series of articles, means for moving the series of articles to compensate for the change in location of said end thereof and maintain said end of the series of articles in generally fixed location within predetermined limits, said means including a ratchet, a connection from the operating means to the means for moving the series of articles, the second mentioned connection including an oscillatable pivoted pawl having an operating portion adapted to engage the ratchet and a follower portion, the operating portion and the follower portion of the pawl extending generally in the same direction from the pivot, the operating portion of the pawl being adapted to operatively engage the ratchet to turn the ratchet and hence move the series of articles upon oscillation of the operating means, a detent normally engaging the surface of the follower portion of the pawl nearer the ratchet axis during oscillation of the operating means maintaining the pawl in an angular position about its pivot in which its operating portion is out of operative engagement with the ratchet and means operated by the first mentioned connection in a predetermined range of amplitude moving the detent out of the path of the follower portion of the pawl permitting the pawl to turn about its pivot so that its operating portion operatively engages and operates the ratchet.

14. Article handling apparatus comprising a feeler, oscillatable operating means, a connection from the operating means to the feeler oscillating the feeler between a position in engagement with the end of a series of articles to be fed seriatim, the location of which end of the series of articles changes during operation of the apparatus, and a position out of engagement with said end of the series of articles, the amplitude of oscillation of the connection varying with the location of said end of the series of articles, means for moving the series of articles to compensate for the change in location of said end thereof and maintain said

end of the series of articles in generally fixed location within predetermined limits, said means including a ratchet, a connection from the operating means to the means for moving the series of articles, the second mentioned connection including an oscillatable pawl pivoted about a generally horizontal axis having an operating portion adapted to engage the ratchet and a follower portion, the operating portion and the follower portion of the pawl extending generally in the same direction from the pivot, the operating portion of the pawl being adapted to be moved by gravity to operatively engage the ratchet to turn the ratchet and hence move the series of articles upon oscillation of the operating means, a detent normally engaging the under surface of the follower portion of the pawl during oscillation of the operating means maintaining the pawl raised with its operating portion out of operative engagement with the ratchet and means operated by the first mentioned connection in a predetermined range of amplitude moving the detent out of the path of the follower portion of the pawl permitting the pawl to move by gravity into operative position wherein its operating portion operatively engages and operates the ratchet.

15. Material handling apparatus comprising a feeler, an oscillatable operating member, a connection from the operating member to the feeler oscillating the feeler between a downward position in engagement with the top of a pile of material whose height changes during operation of the apparatus and an upward position above and out of engagement with the top of the pile, the amplitude of oscillation of the connection varying with the elevation of the top of the pile, pile moving means including a ratchet for changing the elevation of the pile to compensate for its change in height and maintain its top at approximately a fixed elevation, a connection from the operating member to the pile moving means, the second mentioned connection including a pawl pivoted to the operating member, the pawl having an operating portion and a follower portion extending generally in the same direction from the pivot, the operating portion of the pawl being adapted to operatively engage the ratchet to turn the ratchet and hence change the elevation of the pile upon oscillation of the operating member, a detent normally engaging the surface of the follower portion of the pawl nearer the ratchet axis during oscillation of the operating member maintaining the pawl in an angular position about its pivotal connection with the operating member in which its operating portion is out of operative engagement with the ratchet and means operated by the first mentioned connection in a predetermined range of amplitude moving the detent out of the path of the follower portion of the pawl permitting the pawl to turn about its pivotal connection with the operating member so that its operating portion operatively engages and operates the ratchet.

ANDREW NEUHART.
